UNITED STATES PATENT OFFICE.

MALCOLM WALKER, OF LANGSIDE, GLASGOW, SCOTLAND, ASSIGNEE TO SMITH AND COVENTRY LIMITED, OF SALFORD, ENGLAND.

BUFFER AND CUSHION FOR PLANING-MACHINES AND OTHER MACHINES HAVING RECIPROCATING PARTS.

1,263,970.

Specification of Letters Patent. Patented Apr. 23, 1918.

Application filed February 29, 1916. Serial No. 81,287.

To all whom it may concern:

Be it known that I, MALCOLM WALKER, a British subject, residing at Langside, Glasgow, Scotland, have invented certain new and useful Improvements in Buffers and Cushions for Planing-Machines and other Machines Having Reciprocating Parts, of which the following is a specification.

This invention relates to apparatus for cushioning the reciprocating table of planing machines or other reciprocating parts of machines.

It consists of a magnetic buffer comprising one or more magnetic solenoids affixed 15 to the side or framing of the machine with dogs or catches on the reciprocating table or part of the machine to engage and move the core of the solenoid out of its coil at the end of each traverse.

20 The invention will be fully described with reference to the accompanying drawings in which it is shown applied to a planing machine.

Figure 1 is a side elevation.

25 Fig. 2 is an end elevation.

Fig. 3 is a detail of lever arm and roller H.

Fig. 4 is a side elevation showing a modified arrangement.

30 On one or both sides of the framing A on which the table B travels I mount one or more electric solenoids C according to the size and weight of the reciprocating table.

35 Each solenoid is constructed with a soft metal core D mounted to slide horizontally, a magnetic coil E and a cast iron or other housing by which it is affixed to the frame A.

40 Where two or more solenoids are employed on one side of the frame they are preferably mounted tandem, the cores D being mounted at intervals upon a non-magnetic rod or bar F extending lengthwise of the machine.

The rod or bar F may be made of delta metal, brass, wood, or other non-magnetic 45 material. The solenoids are connected preferably in series though they may be wired separably or otherwise if found more convenient.

50 Instead of being mounted horizontally as shown in Figs. 1 and 2 the solenoids may be mounted vertically as shown by Fig. 4 and the cores D be connected by bell crank levers d or other similar devices with a hori-

zontal longitudinally sliding rod or bar by which the cores are operated at the end of each traverse of the machine.

The traveling table B is fitted with adjustable dogs G of ordinary construction.

The rod F is fitted with an arm or lever f or its equivalent with which one of the dogs G on the reciprocating table engages at the end of each traverse and moves the rod to the right or left carrying the solenoids along with it. As shown the arm f is formed with a slot f' with a roller H 60 mounted within the slot or recess f' the journals of the roller traversing plates K with inclined ends. The dogs strike the roller H and carry it and the bar or rod F along with them. Should the table travel too far 70 in either direction the journals of the roller H run down the inclines of the plates K and the roller drops entirely within the slot f' and thus disengages with the dog 75 and prevents damage to the solenoids.

The solenoid cores are thus moved through the solenoid coils at the end of each traverse first in one direction and then in the other and each time act as a buffer to stop the traverse and in returning to accelerate 80 the table in reverse direction.

A switch S is mounted on the end of a spring-controlled rod N, the movement of which is effected by the levers M when operated upon by the dogs G on the table. Normally the switch acts to reduce the current passing through the solenoids during the greater part of the traverse of the table when it is not required, but at the end of the traverse one of the dogs engages and moves 85 one of the levers M to switch on the full strength of the current before the dog G engages the projecting roller or part of the arm f by which the rod F and solenoid cores D are moved. A handle m is connected to one of the levers M to operate the switch by hand.

What I claim as my invention and desire to protect by Letters Patent is:—

1. In a machine having a frame with a reciprocating table thereon, a magnetic solenoid mounted on the frame and provided with a core, means co-operating with the core and by which the latter is moved against the attractive force of the magnetic solenoid, 105 and means for automatically increasing the

current passing through the solenoid when the reciprocating table reaches the end of its movement.

2. In a machine having a frame with a reciprocating table thereon, a plurality of magnetic solenoids provided with cores movable to and fro therein, means attached to the cores by which they are operated at the end of each traverse of the reciprocating table, and means for preventing damage to the solenoids should the table travel too far in either direction.

3. In a machine with a reciprocating table the combination with the framing of a magnetic solenoid attached thereto, a reciprocating core therein, an arm connected therewith and projections attached to the reciprocating table, to engage the arm of the reciprocating core at the end of each traverse.

4. In a machine with a reciprocating table the combination therewith of a plurality of magnetic solenoids attached to the framing, reciprocating cores moving therein, rods connecting the several cores, and an arm projecting therefrom with which the reciprocating table engages at the end of each traverse to draw the cores out of the solenoids against the attractive force of the magnetic coils.

5. In a machine with a reciprocating part,

the combination with the machine framing, the reciprocating table and projecting dogs affixed to the table of magnetic solenoids attached to the framing, cores capable of movement to and fro in the solenoids, rods connecting the cores, an arm attached thereto provided with a slot in the upper edge, plates at both sides of the arm, and a roller mounted upon the side plates and within the slot to be engaged by the projecting dogs on the reciprocating table.

6. In a machine with a reciprocating table the combination with the machine framing the reciprocating table and projecting dogs affixed to the table of magnetic solenoids mounted upon the framing, solenoid cores capable of movement to and fro, rods connecting the solenoid cores, an arm attached thereto with which the projecting dogs engage and means to increase the electric current at the end of each traverse as the solenoids come into action.

Dated this 26th day of January 1916.

In testimony whereof I have hereunto set my hand in presence of two subscribing witnesses.

MALCOLM WALKER.
